MILTON T. THOMPSON, OF KEOKUK, IOWA.

ABUTMENT.

1,199,441.

Specification of Letters Patent. Patented Sept. 26, 1916.

Application filed June 30, 1913. Serial No. 776,525.

To all whom it may concern:

Be it known that I, MILTON T. THOMPSON, a citizen of the United States of America, residing at the city of Keokuk, State of Iowa, have invented a certain new and useful Abutment, of which the following is such a full, clear, and exact description as will enable any one skilled in the art to which it appertains to make and use the same, reference being had to the accompanying drawings, forming part of this specification.

My invention relates to a novel form of abutment and retaining wall for bridges or viaducts, being particularly adapted for use where a stream or other obstacle is crossed by means of fills of earth or other material in combination with one or more bridge spans, and its object is to produce an entirely efficient and satisfactory structure of this character which can be constructed much more cheaply than any form of abutment now in use.

Heretofore, in constructing abutments, it has been necessary to erect a massive column of stone or other material whose weight would be sufficient to cause it to permanently resist the stresses to which it is subjected tending both to overturn it and push it from its foundations. My improved form of abutment can, however, be built with a relatively small quantity of material, the various stresses being resisted in the manner hereafter pointed out.

In the accompanying drawings, Figure 1 is a side elevation; Fig. 2, a plan view of the abutment; and Fig. 3, a front elevation.

The abutment is formed from concrete, located on a suitable foundation, the front portion being semicircular and having tangential continuations or projections 2. In the upper edge of the central portion a bridge seat 3 is formed. The upper edge of the wall slopes downwardly from each side 45 of the bridge seat in substantial conformity to the natural maximum slope of an earth fill. The upper edges of the tangential continuations are provided with downwardly inclined faces 4 and these continuations 50 tend into and under the earth or other material of the fill.

5 are reinforcing rods spaced as shown and extending longitudinally from one extremity of the abutment to the other and 55 preferably positioned midway between the

outer and inner faces. It will be noted that the highest rod 5 shown in the drawings has its central portion positioned near the top of the abutment. The lines 6 in Fig. 2 represent the outline the toe of a fill will 60 naturally assume when applied to the abutment, and the lines 7 in Figs. 1 and 3, the slope of the fill along the outer face of the abutment.

The abutment is subjected to a bursting 65 pressure and the semicircular form of the front makes it possible to resist this pressure with a smaller quantity of material than necessary with other forms. This is due to the fact that the stresses set up in the 70 semicircular structure by the pressure of the fill are all in the direction of the longitudinal axes of the reënforcing members and, therefore, neither the wall as a whole, nor any part thereof, is ever called upon to act 75 as a beam or a slab, as is the case where pressure is applied to a plane surface supported at either extremity or at various points. The tangential termini, being 80 buried under the slope of the earth, prevent the pressure generated by the fill inside the semicircle causing it to spread apart or become distorted. The steel or iron reinforcing rods are strained in direct proportion 85 to the pressure of the material retained and equally all the way around the wall.

The pressure of the material within the abutment also tends to overturn it and to slide it off its foundation. These tendencies are resisted by the fact that the shape of 90 the abutment is such that the center of gravity falls much farther back from its face than if the same amount of concrete were employed in the ordinary way. In addition to this, the burial of the extremities 95 adds greatly to the stability both on account of the direct pressure of material resting over these extremities and on account of the skin friction or adhesion on their inside and outside faces.

Employing the invention herein described, I have built an abutment twenty-six feet high but only fifteen inches thick from bottom to top, which has stood several months without showing any sign of strain or disalignment. An abutment of this height built in the ordinary way would require about four times as much material and would even then be less dependable as a 105 permanent structure.

Having fully described my invention, what I claim as new and desire to secure by Letters-Patent of the United States is:

1. A unitary concrete abutment and retaining wall for earth fills, comprising a substantially semi-circular portion and long rearwardly extending continuations of the walls of said portion having inclined upper edges and extending a substantial distance into and under the earth of the fill, the weight of said continuation walls, the skin friction between them and the earth and the weight of the earth above them sufficing to resist the pressure of the earth of the fill tending to overturn the abutment, and means reinforcing the wall in the direction of its length.

2. A unitary concrete abutment and retaining wall for earth fills, of substantially uniform thickness throughout, comprising only a substantially semi-circular portion, the upper edge of said portion sloping downwardly from each side of the center to conform to the natural slope of the fill, and long rearwardly extending continuations of the walls of said semi-circular portion having inclined upper edges and extending a substantial distance into and under the earth of the fill, the weight of said continuation walls, the skin friction between them and the earth and the weight of the earth above them sufficing to resist the overturning pressure of the earth of the fill, and

the earth on the outer sides of the continuation walls sufficing to resist the spreading stress of the fill between the walls, and spaced, continuous, reinforcing members extending through the abutment from end to end.

3. A unitary concrete abutment and retaining wall for earth fills, comprising only a substantially semicircular portion, the upper edge of said portion sloping downwardly from each side of the center, and long rearwardly extending continuations of the walls of said portion extending a substantial distance into and under the earth of the fill, the weight of said continuation walls, the skin friction between them and the earth and the weight of the earth above them sufficing to resist the overturning pressure of the earth of the fill, and a continuous reinforcing member in the abutment extending from one continuation wall through the upper part of the semicircular portion to the other continuation wall to transmit the overturning movement from the highest portion of the abutment to the continuation walls.

In testimony whereof, I have hereunto set my hand and affixed my seal in the presence of the two subscribing witnesses.
